UNITED STATES PATENT OFFICE

2,583,458

MACHINE FOR MINING AND LOADING COAL

Lawrence L. Wylam, Welch, W. Va.

Application April 27, 1950, Serial No. 158,517

3 Claims. (Cl. 262—19)

1

This invention relates to a mining machine, and more particularly to a machine for use in mining and loading coal.

The object of the invention is to provide a machine which includes a plurality of high speed cutters, whereby coal or other material can be readily mined and loaded, the machine affording a maximum of safety to the miners.

Another object of the invention is to provide a machine which will cut coal in the mine in such a manner that no ribs or other projections will be left remaining to interfere with the operation of the machine, the high speed cutters of the machine of the present invention adapted to be adjusted both as to speed and direction, and wherein the machine is mobile and adapted to be propelled through the mine by a power means which is under control of the operator.

Still another object of the invention is to provide a mining and loading machine which is mobile and includes rotary cutters that are adapted to be driven at a very high rate of speed, whereby coal and the like can be cut or mined and discharged onto a conveyor which is attached to the machine so that the coal can be fed to a suitable receiving mechanism.

A further object of the invention is to provide a planing and loading machine which is adapted to move in a forward or reverse direction, so that pillars of coal can be cut as desired and with a minimum of labor and time required, the machine of the present invention eliminating the necessity of drilling, blasting or other dangerous jobs that are normally performed in a coal mine.

Other objects and advantages will be apparent during the course of the following description.

In the accompanying drawings forming a part of this application, and in which like numerals are used to designate like parts throughout the same:

Figure 1 is a transverse, vertical, sectional view taken through the mining machine of the present invention;

Figure 2 is a top plan view of the machine of the present invention, with the cover or top wall removed from the housing;

Figure 3 is a sectional view taken on the line 3—3 of Figure 1;

Figure 4 is a sectional view taken on the line 4—4 of Figure 2;

Figure 5 is an sectional view taken on the line 5—5 of Figure 1;

Figure 6 is an enlarged sectional view taken on the line 6—6 of Figure 1;

Figure 7 is a schematic wiring diagram illustra-

2

ting the control circuit for the machine of the present invention.

Referring in detail to the drawings, the numeral 20 designates a hollow housing which is adapted to be supported on a suitable frame 21, the housing 20 including a vertically disposed front wall 22, a vertically disposed rear wall 23 which is arranged in spaced, parallel relation to the rear of the front wall 22, and a pair of spaced, parallel, vertically disposed side walls 24 and 25. The housing 20 further includes a horizontally disposed bottom wall 26 and a horizontally disposed top wall or cover 27 which may be detachably connected to the housing.

Extending rotatably through the side wall 24 is a pair of horizontally disposed axles 28 and 29, while extending rotatably through the other side wall 25 of the housing is a second pair of axles 30 and 31, Figure 2. A ground-engaging wheel 32 is mounted on the outer end of the axle 28, while a similar wheel 33 is mounted on the outer end of the axle 29, there being wheels 34 and 35 mounted on the other pair of axles 30 and 31.

Arranged in the housing 20 and supported on the bottom wall 26 is an electric motor 36 which is adapted to rotate a short drive shaft 37. The drive shaft 37 is connected to a reducing gear assembly 38, and the reducing gear assembly 38 serves to drive an endless chain 39 which is arranged in engagement with a shaft 40. The endless chain 39 serves to rotate or drive the axle 29. The motor 36 is of the reversible type, so that the wheel 33 can be driven in either a forward or rearward direction. A second endless chain 41 is also arranged in engagement with the shaft 40, and the endless chain 41 serves to rotate or drive the axle 28 so as to rotate the wheel 32 in a forward or reverse direction. A similar arrangement is provided for driving the other pair of wheels 34 and 35 in a forward or reverse direction. Thus, a reversible electric motor 42, which is arranged in the housing 20, serves to actuate a suitable reducing gear mechanism, and this last-named reducing gear mechanism serves to drive the endless chain 44, the chain 44 being arranged in engagement with the axle 31. The endless chain 44 is also operatively connected to an endless chain 45, and the chain 45 is connected to the axle 30, whereby the motor 42 serves to rotate the wheels 34 and 35 in a forward or reverse direction.

Arranged rearwardly of the housing 20 and connected to the back wall 23 in any suitable manner is an inclined conveyor 46. The con-

veyor 46 includes an endless wide belt 47 which has a plurality of spaced, parallel angle irons 48 secured thereto, so that coal that has been mined or cut can be conveyed upwardly to a desired receiving receptacle or member. The endless belt 47 is trained over a first shaft 49, and a second shaft 50. The coal or other material that has been mined may be conveyed or discharged by the conveyor 46 onto a wide belt 51, and the belt 51 may be used to transport or convey the coal to any desired location in the mine.

For driving or operating the conveyor 46, an electric motor 52 is supported in the housing 20, the motor 52 serving to drive a reducing gear mechanism 54 which in turn actuates an endless chain 53. The endless chain 53 is arranged in engagement with a sprocket 55 which is mounted on an end of the shaft 50, so that actuation of the motor 52 causes continuous movement of the endless belt 47 of the conveyor 46.

The cutting mechanism for planing or cutting the coal, salt or other material in the mine is designated generally by the numeral 59, and for directing the coal or other material that has been cut by the cutting mechanism 59 onto the lower end of the conveyor 46, a scoop 56 is provided. The scoop 56 includes a front section 57 and a wide, rear section 58, Figure 2.

The cutting mechanism 59 includes a support member 60, Figure 5, which projects through an opening or cutout 61 in the side wall 24 of the housing. The support member 60 is provided with rectangular recesses or grooves 62 for slidably receiving therein the side wall 24. The support member 60 is also provided with a circular opening 63. Rotatably arranged in the opening 63 is a disc portion 64 of a body member 65. A plate 66 is secured to the disc portion 64 by suitable securing elements, such as screws 67, and a stub shaft 68 projects from the plate 66 for a purpose to be later described. Projecting from the inner surface of the support member 60 and secured thereto is a pair of stub shafts 69 and 70, the purpose of which is later described in this application.

Rotatably supported by the body member 65 is a drive shaft 71, the drive shaft 71 projecting through an arcuate slot 72, Figure 3, which is arranged in a portion of the body member 65, so that there will be no jamming when the cutting mechanism 59 is swung about a horizontal axis.

A universal joint 73 pivotally connects the inner end of the drive shaft 71 to a shaft section 74, while a similar universal joint 75 serves to pivotally connect the other end of the shaft section 74 to a second shaft section 76. Arranged in the housing 20 is an electric motor 77 which serves to operate an endless chain 78, and the chain 78 is arranged in engagement with the shaft section 76. Thus, actuation of the motor 77 causes rotation of the drive shaft 71, whereby the various cutters of the mechanism 59 will be actuated as later described.

Mounted on the drive shaft 71 is a gear 79 which is arranged in meshing engagement with a gear 80, the gear 80 being connected to a straight shaft 81 by means of a key 82, Figure 5. The straight shaft 81 is arranged at right angles with respect to the shaft 71. Arranged in spaced, parallel relation with respect to the drive shaft 71 and rotatably supported by the body member 65 is a driven shaft 83, there being a gear 84 mounted on the driven shaft 83, and

the gear 84 meshes with the gear 80 on the straight shaft 81. Thus, rotation of the drive shaft 71 causes rotation of the straight shaft 81 and also of the driven shaft 83. Mounted on the straight shaft 81 is a pair of cutting members 85 and 85', each of the cutting members 85 and 85' including a plurality of teeth 86 which serve to mine or cut the coal when the machine is being used. The cutting members 85 and 85' are adapted to be driven at a very high rate of speed.

Mounted on the front end of the drive shaft 71 is a circular cutter 87, while mounted on the front end of the driven shaft 83 is a similar circular cutter 88. The circular cutters 87 and 88 are arranged or positioned in the space between the pair of cutting members 85 and 85', and the purpose of the circular cutters 87 and 88 is to cut or plane any coal that would not be cut or mined by the cutting members 85 and 85', so as to insure that there will be no ribs or projections left during the mining operations.

A hydraulic means is provided for vertically adjusting the position of the cutting mechanism 59, and also for swinging or pivoting the cutting mechanism 59 about a horizontal axis. This means comprises an electric motor 89 that is arranged in the housing 20, the motor 89 adapted to drive a pump 90, which is arranged contiguous to the motor 89.

Arranged adjacent to the side wall 24 of the housing is a plurality of hydraulic cylinders. Thus, a hydraulic cylinder 91, which includes a casing 92, has a rod 93 reciprocably mounted therein, and the upper end of the rod 93 is connected to the stud shaft 69. Arranged in spaced, parallel relation with respect to the cylinder 91 is a second hydraulic cylinder 94 which includes a hollow casing 95 having a reciprocating rod 96 arranged therein, the upper end of the rod 96 being connected to the other stud shaft 70. Thus, by directing hydraulic fluid into the top or bottom of the casings 92 and 95, the entire body member 65 can be raised or lowered, whereby the cutting mechanism 59 can be adjusted vertically so as to permit the coal to be cut or mined at any desired elevation. Arranged adjacent to the cylinder 91 is a hydraulic cylinder 97 which includes a hollow casing 98 having a reciprocating rod 99 arranged therein, the rod 99 having its upper end pivotally connected to the stud shaft 69. Upon proper actuation of the cylinder 97, the plate 66 will be caused to rotate, and this in turn will result in rotation or swinging movement of the body member 65 about a horizontal axis, so that the cutting mechanism 59 can be moved to and from a horizontal or vertical position.

Suitable conduits are provided for conveying the hydraulic fluid to and from the pump 90 and to and from the tops and bottoms of the previously-described hydraulic cylinders. A pair of valves 101 and 102 are provided for controlling the flow of hydraulic fluid to and from the pair of cylinders 91 and 94, and by properly setting these valves, the hydraulic fluid can either be directed into the bottoms of the cylinders or into the tops thereof, so as to vertically adjust the cutting mechanism. A second pair of valves 103 and 104 are provided for controlling the flow of fluid to the cylinder 97 from the pump 90 and back again. These valves are adapted to be actuated or set by electrically controlled means, as described later in this application.

A manually operable means is provided for con-

trolling the actuation of the various motors and hydraulic system arranged in the housing 20, and this manually operable means is arranged exteriorly of the housing 20 and at a convenient distance therefrom. Thus, a control box 105 is secured to the exterior of the side wall 25, and a plurality of hand-engaging levers are operatively connected to the control box 105, Figure 2. A lever 106 is adapted to be actuated when the wheels on the right side of the machine are to be driven in a forward or reverse direction. Similarly, a lever 107 is adapted to be actuated when the wheels on the left side of the machine are to be driven in a forward or reverse direction. The motor 77 for driving the cutting mechanism is actuated by proper movement of a lever 108, while the motor 89 for actuating the hydraulic pump 90 is actuated by a suitable lever 109. A lever 110 is adapted to be actuated in order to properly energize solenoids 114 and 115, and this actuation of the solenoids 115 and 114 is used to properly set the valves 101 and 102 so as to effect vertical adjustment of the cutting mechanism 59. The lever 111 is provided for actuating a pair of solenoids 116 and 117, Figure 2, and actuation of the solenoids 116 and 117 serves to set or move the valves 103 and 104 to a desired position, whereby the cylinder 97 is actuated to thereby cause rotation or pivotal movement of the entire cutting mechanism 59. The conveyor motor 52 is adapted to be actuated by a manually operable lever 112, and finally, a lever 113 is provided for actuating a main switch 118, Figure 7.

Referring to Figure 7 of the drawings, there is shown a portion of the electrical circuit whereby movement of the levers causes actuation of the various motors. The circuit includes a pair of lines 119 and 120 which are adapted to be connected to any suitable source of electrical energy, and the main switch 118 is provided for at times breaking the circuit or making the circuit complete between the lines 119 and 120. A rheostat 123 is connected across the lines 119 and 120 by means of wires 121 and 122, the conveyor motor 52 being connected in series with the line 121. The rheostat 123 is actuated by proper movement of the lever 112.

The pair of solenoids 116 and 117 are connected in parallel with the lines 119 and 120 by a pair of wires 124 and 125, and a switch 126 is connected to the lines 124 and 125, the switch 126 adapted to be actuated by the lever 111, so as to selectively energize the solenoids 116 and 117, whereby the valves 103 and 104 can be set or adjusted to their desired positions. A similar pair of lines 127 and 128 connect the solenoids 114 and 115 to the wires 119 and 120, and a switch 129 is arranged in this last-named circuit. The switch 129 is adapted to be actuated by the lever 110, whereby the valves 101 and 102 can be set to the desired positions so as to raise or lower the cutting mechanism 59.

The motor 89 for actuating the hydraulic pump 90 is connected in parallel with the lines 119 and 120 by a pair of wires 130 and 131, and a rheostat 132 connects electrically the wires 130 and 131 together. The rheostat 132 is adapted to be actuated by the lever 109 so as to permit actuation of the hydraulic pump as desired. A pair of lines or wires 133 and 134 connect the cutting mechanism motor 77 to the circuit, and a rheostat 135 is electrically connected to the wires 133, and 134. The rheostat 135 is actuated by proper manipulation of the lever 108, whereby the motor for driving the cutting mechanism can be turned

on and off or the speed thereof varied by proper positioning of the movable portion of the rheostat 135.

Similarly, the reversible electric motor 42 for driving the pair of wheels 34 and 35 is electrically connected to the lines 119 and 120, and the other reversible electric motor 36 is electrically connected to these lines also, the motor 36 being used for rotating the wheels 32 and 33 in either a forward or reverse direction. A switch 136 is electrically connected to the motor 42, and the switch 136 is adapted to be actuated by means of the lever 107, while the switch 137 for controlling the direction of rotation of the motor 36 is controlled by the lever 106.

The machine of the present invention is especially suitable for use in mining coal, and will enable increased quantities of coal to be cut or mined with a minimum amount of effort and expense. The machine is propelled along the ground by means of the wheels 32, 33, 34 and 35, and the machine can either be moved in a forward or reverse direction by proper manipulation of the levers 106 and 107, since these levers control the switches 136 and 137 which determine the direction of rotation of the motors 36 and 42. The cutting mechanism 59 includes the pair of cutting members 85 and 85' which rotate at a very high speed, so as to shear or plane the coal in a highly efficient manner, and the speed of rotation of these members can be controlled by actuation of the lever 108 which controls the rheostat 135, the rheostat 135 being electrically connected to the motor 77. The vertical position of the cutting mechanism 59 can be adjusted by actuation of the lever 109, whereby the rheostat 132 will be energized so that the pump motor 89 can be controlled to force hydraulic fluid into the cylinders, the valves 102 through 104 having been previously set by actuation of the levers 110 and 111. It is to be noted that the cutting mechanism 59 can also be swung about a horizontal axis by means of the lever 111. The conveyor 46 arranged rearwardly of the machine receives the coal or other material that has been cut by the mechanism 59 and this conveyor 46 is driven by the motor 52, the motor 52 being controlled by the rheostat 123 which in turn is under control of the lever 112. It is to be noted that all of these levers project at a safe distance from the machine so that the operator of the machine can work in the highest degree of safety. The motor 77 actuates the chain 78, which in turn actuates the drive shaft 71 to thereby cause actuation of the cutting mechanism 59.

The machine of the present invention is adapted to move across a pillar of coal or can be used in mines of various sizes. The cutting mechanism 59 is adapted to be driven at an extremely high velocity, the rate of rotation of the members 85 and 85' depending upon the material being cut. The machine can be used for driving tunnels or narrow entries into a mine, and can also be used for pillar extraction in mines. The machine of the present invention can also be used for mining salt as well as coal, and other materials may readily be mined or loaded with the machine of the present invention.

I claim:

1. In a mining machine, a frame, a hollow housing supported on said frame and including spaced parallel vertically disposed side and end walls, a horizontally disposed bottom wall and a horizontally disposed top wall, a pair of horizontally disposed axles projecting through each

side wall of said housing, a first pair of wheels connected to a pair of said axles, a second pair of wheels connected to the other pair of axles, a first electric motor arranged in said housing and supported on said bottom wall, chain-and-sprocket means connecting said first motor to one pair of axles, a second motor arranged in said housing and supported on said bottom wall, chain-and-sprocket means connecting said second motor to the other pair of axles, a conveyor arranged rearwardly of said housing and connected thereto, a third electric motor arranged in said housing and operatively connected to said conveyor, a scoop arranged along one side of said housing for directing material onto said conveyor, a cutting mechanism operatively connected to said housing, said cutting mechanism comprising a body member adjustably connected to a side wall of said housing, a drive shaft supported by said body member, a fourth electric motor arranged in said housing and operatively connected to said drive shaft, a straight shaft arranged at right angles with respect to said drive shaft, a driven shaft arranged in spaced parallel relation with respect to said drive shaft and supported by said body member, gear means connecting said straight shaft to said drive and driven shafts, a pair of spaced cutting members mounted on said straight shaft and each provided with cutting teeth, and a circular cutter connected to the outer ends of said drive and driven shafts.

2. The apparatus as described in claim 1, and further including manually operable means arranged exteriorly of said housing for regulating said motors.

3. In a mining and loading machine, a frame, a hollow housing supported on said frame and including side and end walls, a bottom wall and a top wall, a pair of axles projecting through each side wall of said housing, a first pair of

wheels connected to a pair of said axles, a second pair of wheels connected to the other pair of axles, a first electric motor arranged in said housing and supported on said bottom wall, means connecting said first motor to one pair of axles, a second motor arranged in said housing and supported on said bottom wall, means connecting said second motor to the other pair of axles, a conveyor arranged rearwardly of said housing and connected thereto, a third electric motor arranged in said housing and operatively connected to said conveyor, a scoop arranged along one side of said housing for directing material onto said conveyor, a cutting mechanism operatively connected to said housing, said cutting mechanism comprising a body member adjustably connected to a side wall of said housing, a drive shaft supported by said body member, a fourth electric motor arranged in said housing and operatively connected to said drive shaft, a straight shaft arranged at right angles with respect to said drive shaft, a driven shaft supported by said body member, means connecting said straight shaft to said drive and driven shafts, a pair of spaced cutting members mounted on said straight shaft and each provided with cutting teeth, and a circular cutter connected to the outer ends of said drive and driven shafts.
